UNITED STATES PATENT OFFICE.

J. A. McCLELLAND, OF LOUISVILLE, KENTUCKY.

IMPROVEMENT IN DENTAL PLATES.

Specification forming part of Letters Patent No. 39,538, dated August 11, 1863.

To all whom it may concern:

Be it known that I, J. A. McCLELLAND, of Louisville, in the county of Jefferson and State of Kentucky, have invented a new and useful Improvement in Dental Plates; and I do hereby declare that the following is a full, clear, and exact description of the same, reference being had to the accompanying drawings, forming part of this specification, in which—

Figure 1 is a top view of a plate constructed according to my invention. Fig. 2 is a central vertical section of an upper set of teeth applied to such plate.

Similar letters of reference indicate corresponding parts in both figures.

The subject of my said invention is a metallic dental plate so constructed and arranged that vulcanized india-rubber may be used in connection with it, thus combining the perfect adaptability of the rubber to the mouth with the strength of metal. This may be effected by using a closely-woven or perforated web or plate of gold or other metal, through which the rubber may connect from side to side, rendering the plate air-tight.

In order that others skilled in the art to which my invention appertains may be enabled to fully understand and use the same, I will proceed to describe more fully the preferred mode of carrying it into effect.

The drawings represent the skeleton *a* as being composed of a web of platinum, gold, or other metal wire interwoven after the manner of wire-gauze; but, instead of this web, I propose to use as an equivalent in some cases a thin plate of suitable metal, closely and finely perforated.

To manufacture my improved plate, after having cut or otherwise wrought the web or perforated plate which forms the skeleton to a suitable shape for the denture, I fit it as closely as possible to the plaster model of the mouth and then apply the india-rubber *b* upon it, and afterward proceed with the work in the manner commonly practiced with a plate of india-rubber alone, and in so doing a sufficient quantity of the india-rubber will be forced through the reticulations or perforations of the metallic web or skeleton plate to make a perfect adaptation to the plaster model and present a smooth surface to come in contact with the mouth.

I am aware that it has been proposed to insert or mold metallic strips or wires in porcelain to be used as a base for artificial teeth. This I do not claim.

Having thus described my invention, what I claim as new therein, and desire to secure by Letters Patent, is—

1. The employment or use of a metallic dental plate, closely perforated or woven, so that india-rubber may penetrate and adhere to it, as described.
2. The combination, in a dental plate, of a skeleton or plate of woven or perforated metal with a base or filling of vulcanized india-rubber, in order to unite the perfect adaptability of rubber to the mouth with the strength of metal, substantially as explained.

J. A. McCLELLAND.
